UNITED STATES PATENT OFFICE

ERNST S. H. BAARS, OF MILWAUKEE, WISCONSIN, ASSIGNOR TO THE VILTER MANUFACTURING COMPANY, OF MILWAUKEE, WISCONSIN, A CORPORATION OF WISCONSIN

REFRIGERATING APPARATUS

Application filed September 4, 1931. Serial No. 561,147.

The present invention relates in general to improvements in the art of refrigeration, and relates more specifically to improvements in the construction and operation of control mechanisms for refrigerating systems utilizing liquid refrigerant and ordinarily comprising a compressor, an evaporator, and a condenser constituting a confining circuit for the liquid.

10 An object of the invention is to provide an improved control mechanism for refrigerating systems or the like, which is simple in construction and efficient in operation.

Another object of the invention is to provide an improved refrigerant feed valve which will permit most economical and efficient operation of the system with which the valve is associated.

20 A further object of the invention is to provide a simple valve structure which will permit effective delivery of liquid refrigerant to cooling coils and other surfaces disposed above the valve structure.

Still another object of the invention is to provide an improved feeding device which will force liquid refrigerant to the most desirable points of a system, from an operating view.

Another object of the invention is to provide an improved feeder for delivering refrigerant to a number of independent systems, through a common valve structure.

30 A further object of the invention is to provide a feed valve for refrigerating systems, which will prevent flash gas and liquid slugs from creating disturbances in the system utilizing the valve.

Still another object of the invention is to provide an improved feed control which permits effective control of the refrigerant, and which does not permit undesirable over-feeding of refrigerant as in the so-called high pressure float feed systems heretofore proposed.

40 Another object of the invention is to provide an improved float control wherein a relatively small float may be employed to effectively control large capacity valves.

50 A further object of the invention is to provide a feed regulator which will operate

equally well at variable temperatures, and which will not ordinarily be affected by congealing of oil due to shutting down of the system utilizing the regulator.

Still another object of the invention is to provide improved control valve structures which will eliminate undesirable variations in pressure in a system, such as might tend to produce objectionable irregularities in evaporation of the refrigerant.

Another object of the invention is to provide an improved float controlled valve which may be conveniently manufactured, assembled and installed, and which is automatic in operation.

These and other objects and advantages will be apparent from the following detailed description.

A clear conception of a number of embodiments of the invention and of the construction and mode of operating feed valves and cooling systems built in accordance with the improvement, may be had by referring to the drawings accompanying and forming a part of this specification in which like reference characters designate the same or similar parts in the various views:

Fig. 1 is a longitudinal central vertical section through one of the improved float controlled liquid feed valves;

Fig. 2 is an end view of the feed valve casing;

Fig. 3 is an opposite end view of the feed valve casing;

Fig. 4 is a diagram of one type of refrigerating system having one of the improved float controlled feed valves incorporated therein;

Fig. 5 is an end view of the upper coil of the evaporator used in the system of Fig. 4, a section having been taken through the coil along the line 5—5 of Fig. 4;

Fig. 6 is a diagram of a portion of a milk or other liquid cooling system utilizing one of the improved float controlled regulating valves;

Fig. 7 is a diagram of a portion of a multiple room refrigeration system embodying one of the improved feed valves;

Fig. 8 is a sectional diagram of a special

cooling coil or evaporator adapted for cooperation with the improved valve;

Fig. 9 is an enlarged transverse section through the coil of Fig. 8, the section being taken on the line 9—9 of Fig. 8;

Fig. 10 is a diagram of a portion of a simple form of milk and water cooler showing the application of one of the improved valves; and

10 Fig. 11 is a diagram of a refrigerating system embodying one of the improved valves, wherein the refrigerant from the valve is discharged below the level of the liquid refrigerant in the system.

15 Referring to Figs. 1, 2 and 3, the improved float controlled feed regulating valve comprises in general a supporting member 14 having a central horizontal bore 15 and a concentric port 16 formed therein; a plunger 17 snugly fitting and slideable within the bore 15 and having an integral needle valve 18 of reduced diameter cooperable with the port 16; a circular casing 19 rigidly but detachably attached to the supporting member 14 20 and cooperating therewith to form a float chamber 20; a float 21 disposed within the chamber 20 and swingably supported upon the member 14 by means of a pivot 22; a bent lever 23 attached to the float stem and extending upwardly across and forwardly over the bore 15; a link 24 pivotally connecting the lever 23 with the end of the plunger 17 remote from the valve 18; a weight 25 adjustably associated with forward extension of the lever 23 within the chamber 20; and suitable pipe connections communicating with the port 16 and chamber 20 through the member 14 and casing 19.

25 The supporting member 14 is preferably 40 formed of a metal casting, while the casing 19 may be formed of a section of standard pipe having a dished sheet metal head attached thereto by welding or otherwise, and also having thimbles similarly attached thereto 45 for the convenient connection of the piping. The joint between the member 14 and casing 19 should be absolutely tight so as to insure hermetic sealing of the chamber 20 which is ordinarily supplied with liquid refrigerant 50 sufficient to raise the float 21. The plunger 17 besides snugly fitting the bore 15, may also be provided with a series of sealing grooves as shown in Fig. 1, in order to prevent passage of liquid from the port 16 through the 55 bore 15 to the chamber 20. The weight 25 may be positioned at any desired point along the forward extension of the lever 23, so as to counter-balance the weight and buoyancy of the float 21 to any desired extent, thus providing for very sensitive regulation of the flow past the needle valve 18. The end surface of the plunger 17 adjacent to the needle valve 18 is also exposed to the pressure at the discharge side of the needle valve, which 60 pressure also tends to counter-act the for-

ward pressure upon the plunger 15 due to the float 21 and any fluid pressure which may exist within the chamber 20.

70 Referring specifically to the diagram of Figs. 4 and 5, the refrigerator system therein illustrated comprises, a pump or compressor 26, a condenser 27, a receiver 28, an accumulator 29, an upper evaporator or cooling coil 30, a lower evaporator or cooling coil 31, one of the improved float actuated control valves, and suitable conduits or pipes connecting these elements of the system. The liquid refrigerant discharged into the receiver 28 from the condenser 27, is delivered to the port 16 of the control valve through a pipe 32, and after passing the needle valve 18 the refrigerant is delivered to the upper coil 30 through the pipe 33. The gases generated in the upper coil 30 due to evaporation, together with the excess liquid, escape from the upper coil 30 through a pipe 34 or a pipe 34' to the upper portion of the accumulator 29. The surplus liquid refrigerant within the accumulator 29 passes into the lower coil through a pipe 35, and the gases from this coil 31 may also enter the accumulator through the pipe 34. The gases collecting in the uppermost portion of the accumulator 29 escape through a pipe 36 to the compressor 26 from whence the compressed gases are delivered through a pipe 37 to the condenser 27 wherein they are condensed for subsequent recirculation through the system.

80 A liquid refrigerant supply pipe 38 connects the lowermost portion of the float chamber 20 with the accumulator 29 below the normal level of the liquid refrigerant in the latter, and a gas escape pipe 39 connects the uppermost portion of the chamber 20 with the accumulator 29 above the normal liquid level. The float chamber 20 may also be provided with drain connection 40 as shown in Figs. 1 and 2. In order to insure 85 efficient distribution of the refrigerant in the upper coil 30, this coil may be provided with upper and lower headers 41, 42 as shown in Fig. 5. The headers 41, 42 besides being interconnected by the several coil sections, are also joined by risers 43, 44, the former of which communicates directly with the pipe 33 and extends above the bottom of the header 41, and the latter of which is flush with the bottom of the header 41 but extends below the top of the header 42. The gas discharge pipe 34 communicates with the uppermost portion of the upper header 41, thus preventing escape of excessive quantities of liquid refrigerant from the cooling coil 30 to the accumulator 29. The normal operation of the system shown in Figs. 4 and 5 should be apparent from the foregoing detailed description of the system.

90 Referring specifically to the diagram of

Fig. 6, the milk cooler has a lower ammonia section 45 provided with a cooling coil 46, and also has a water section 47 superimposed over the lower section 45. The float actuated control valve of this cooling system is connected to the accumulator 29 by means of supply and exhaust pipes 38, 39 exactly as in the system of Fig. 4, and liquid refrigerant is delivered to the needle valve chamber from the receiver, through a pipe 32 and past a liquid stop valve 48 of standard construction. The discharge pipe 33 of the control valve, communicates with the lower end of the coil 46, and this end of the coil may also be directly connected to the lower portion of the accumulator 29 by means of a pipe 49. A by-pass connection 50 having an expansion valve 51 therein, may also be provided between the pipe 32 and the pipe 33 for the purpose of permitting delivery of refrigerant from the receiver to the coil 46 without passing through the control valve. The upper end of the coil 46 is connected to the upper portion of the accumulator 29 by means of a pipe 34, and the suction pipe 36 leading from the top of the accumulator 29 may be provided with special automatic control valves 52, 53 and with an ordinary suction stop valve 54. The control valve 52 is operable by suction pressure to control the suction flow, while the valve 53 is solenoid actuated, being controlled by the quantity or weight of milk or other liquid entering the water section 47 and acting upon a switch 54'. This control may also be effected thermostatically or otherwise in order to prevent excessive cooling of the milk to freezing temperatures. The valves 52, 53 form no part of the present invention, but it is to be noted that in the cooling system of Fig. 6, the float operated control valve is disposed above the cooling coil in order to provide a liquid head for forcing the refrigerant through the cooling coils and connections.

In the diagram of Fig. 7 the single float actuated control valve regulates the delivery of liquid refrigerant directly from a receiver through pipes 32, 33 to the upper end of a cooling coil 55, the lower end of which communicates with a header 56 disposed on the same lever as the float chamber 20, through a pipe 57. A second cooling coil 58 has its upper end connected directly to the header 56 and has its lower end connected to a reservoir 59 which is in turn connected to the header 56 above the liquid level therein, by means of a vertical pipe 60. The uppermost portion of the header 56 is connected to the suction of the compressor by means of a pipe 61, and the supply and exhaust pipes 38, 39 of the control valve, are connected respectively to the pipes 60, 61. In this system, the use of an accumulator is dispensed with, and the single control valve regulates the de-

livery of refrigerant to two coils 55, 58 one of which is disposed above and the other below the regulating valve.

In the diagrammatic sectional views of Figs. 8 and 9, the float operated control valve regulates the delivery of liquid refrigerant from the pipe 32 through the pipe 33 to the upper pipe or section 62 of an evaporator. The upper section 62 has a special overflow arrangement as shown in Fig. 9, consisting of a vertical tube 63 having an open upper end communicating with the gas space within the section 62, and an overflow elbow 64 disposed within the tube 63 and having a V-notch 65 at its upper end for establishing a definite normal level of liquid within the section 62. The pipe 33 discharges liquid refrigerant into the end of the section 62 remote from the overflow, and a gas exhaust pipe 66 connects the upper portion of the opposite end of the section 62 with a header 67 which communicates with the pipes 39, 36 of the system, the latter of which leads to the compressor. The evaporator comprises other sections 68, 69, 70, 71 disposed in series beneath the upper section 62 and likewise interconnected by means of tubes 63 and overflow elbows 64, but the elbows of the lower overflow connections need not have the V-notches therein and overflow only at their uppermost ends. The lowermost section 71 communicates at its liquid discharge end, with the supply pipe 38 for the float chamber 20 and the float valve is disposed in the horizontal plane of the section 71 so as to maintain substantially the same liquid level in the chamber 20 and within the section 71. With this construction of evaporator, the successive sections 62, 68, 69, 70, 71 will contain a basin of liquid refrigerant, but the gases will be free to rise through the tubes 63 and to eventually escape through the exhaust pipe 66. This system likewise avoids necessity of utilizing an accumulator.

In the liquid cooling system of Fig. 10 the improved float actuated regulating valve is adapted to control the flow of liquid refrigerant from the pipe 32 through the pipe 33 to a pipe 72 disposed centrally within the upper section of a coil 73. The lower end of the coil 73 communicates directly with the lower portion of an accumulator 29, and a gas discharge pipe 74 connects the upper end of the coil 73 with the upper end of the accumulator. The supply and exhaust pipes 38, 39 of the control valve communicate with the accumulator, respectively below and above the normal liquid level therein, and the accumulator has a gas delivery pipe 36 communicating with the extreme upper portion thereof the same as in Figs. 4 and 6. Liquid may be admitted to a receptacle 75 disposed adjacent to the coil 73, and the float chamber 20 of the control valve is disposed in the same horizontal plane as the axis of the pipe 136

72. When this system is in operation, it is desirable due to the fact that the operation is ordinarily intermittent, to maintain the liquid level low since considerable boiling action takes place after cooling stops. The liquid will eventually boil down to such an extent that the control valve will act to feed fresh liquid, and this fresh supply will run along the coil surfaces and will evaporate. 10 The flash gas will dry in the portion of the coil 73 between the discharge end of the pipe 72 and the discharge pipe 74.

In the system shown in Fig. 11, it is desired to discharge the liquid refrigerant from the control valve below the liquid level in the accumulator 29 in order to prevent formation of excessive flash gas. As in Fig. 4, the system comprises a compressor 26, a condenser 27, a receiver 28, a float actuated control 15 valve, a cooling coil 76, and pipes connecting the various elements of the system. The compressor 26 has a suction pipe 36 communicating with the upper end of the accumulator 29, and has a discharge pipe 37 connected to the condenser 27. The receiver 28 communicates with the control valve through a pipe 32 and the discharge pipe 33 of this valve communicates with the accumulator 29 below the normal liquid level therein. The 20 coil 76 communicates at its lower end with the lower portion of the accumulator 29, and communicates at its upper end with the upper gas chamber of the accumulator. The supply and exhaust pipes 38, 39 of the float 25 chamber 20, communicate with the accumulator 29 respectively below and above the liquid level, and may be designated as equalizing lines since they function to equalize the pressures in the accumulator and float chambers. 30 This system obviously differs from the others in that the control valve discharges liquid refrigerant as required, directly to the accumulator 29 instead of to the evaporator or cooling coils.

45 From the description of these various diagrams and systems, it will be obvious that the improved float actuated control valve is adapted to be used in conjunction with various types of evaporators of either the flooded or direct expansion type and regardless of whether or not an accumulator is employed in the system. The needle valve 18 is at all times exposed to liquid refrigerant, and the weight 25 may be readily adjusted to produce 50 any desired conditions of operation of the valve 18 by the float 21.

It will be apparent that in each of the several systems illustrated, the liquid level within the float chamber 20 is established by 60 an accumulator 29 or substitute device which receives liquid refrigerant from the charge end of an evaporator or cooling coil. The operation of the float control valve is not directly therefore affected by variations in 65 the conditions at the inlet of the evaporator.

The improved float actuated control valve is adapted to accurately regulate the flow of refrigerant regardless of variations in pressure in the source of supply or at the inlet of the evaporator, and this is true regardless of whether the evaporator inlet is located above, below, or at the level of the liquid in the float chamber 20. The special construction of cooling coil or evaporator shown in Figs. 8 and 9, is especially adapted for cooperation with the improved float controlled regulating valve, and in this embodiment of the invention the lower section 71 of the evaporator may be utilized as an accumulator for establishing the desired liquid level within the float chamber 20. It will be apparent from the foregoing description that all of the objects set forth in the introduction to this specification are effectively attained with the use of the improved float controlled regulating valve, and that this valve has special utility when applied to refrigerating systems of various types.

It should be understood that it is not desired to limit the invention to the exact details of construction herein shown and described, for various modifications may occur to persons skilled in the art.

It is claimed and desired to secure by Letters Patent:—

1. In combination, an evaporator comprising a series of superimposed tubular sections and riser pipes extending from the top of each lower section into and above the bottom of the adjacent upper section, overflow 100 elbows within the upward extensions of said riser pipes terminating below the tops thereof, and a float controlled valve operable by variations in the level of refrigerant in the lower of said sections for delivering refrigerant only to an upper of said sections.

2. In combination, an evaporator comprising a series of superimposed tubular sections and riser pipes extending from the top of each lower section into and above the bottom of the adjacent upper section, overflow elbows within the upward extensions of said riser pipes terminating below the tops thereof, one of said elbows having a V-notch in the overflow edge thereof, and a float controlled valve operable by variations in the level of refrigerant in the lower of said sections for delivering refrigerant to an upper of said sections.

3. In combination, an evaporator comprising super-imposed horizontal tubes and a riser pipe extending from the top of the lower tube into and above the bottom of the upper tube, and an overflow elbow within the upward extension of said pipe, said elbow having an inlet at the bottom of said extension and having a V-notch constituting an overflow edge located beneath the top of said extension.

4. In combination, an evaporator compris-

ing a series of superimposed and interconnected tubular sections, a valve located below the upper of said sections for delivering refrigerant to said evaporator, and a float 5 for controlling the operation of said valve, said float being operable by variations in the level of refrigerant in a lower of said coils.

5. In combination, an evaporator comprising a series of superimposed and interconnected tubular sections, an accumulator receiving liquid refrigerant from a lower of said sections, a valve for delivering refrigerant directly to an upper of said sections, and a float for controlling the operation of 10 said valve, said float being operable by variations in the level of refrigerant in said accumulator.

6. In combination, an upper evaporator, a lower evaporator disposed below said upper evaporator, a header interposed between the outlet of said upper evaporator and the inlet of said lower evaporator, conduit means connecting the outlet of said lower evapora-

tor with said header, a float valve operable by variations in level of the liquid refrigerant in said header for controlling direct delivery of refrigerant to the inlet of said upper evaporator, and means for effecting delivery 70 of gaseous refrigerant from said header.

7. In combination, an upper evaporator, a lower evaporator disposed below said upper evaporator, an upper header interposed between the outlet of said upper evaporator 75 and the inlet of said lower evaporator, a lower header connected to the outlet of said lower evaporator and communicating with said upper header, a float valve operable by variations in level of the liquid refrigerant 80 in said upper header for controlling delivery of refrigerant directly to the inlet of said upper evaporator, and means for effecting discharge of gaseous refrigerant from the upper portion of said upper header. 85

In testimony whereof, I affix my signature.
ERNST S. H. BAARS.
